DESIGN FOR A TIP FOR MARKING IMPLEMENT

John P. Nissen, Jr., Noble, Pa.

Application February 4, 1941, Serial No. 98,737

Term of patent 7 years

To all whom it may concern:

Be it known that I, John P. Nissen, Jr., a citizen of the United States, residing at Noble, in the county of Montgomery and State of Pennsylvania, whose post-office address is % John P. Nissen, Jr. Co., Wyncote, Montgomery County, Pennsylvania, have invented a new, original, and ornamental Design for a Tip for Marking Implements, of which the following is a specification, reference being had to the accompanying drawing, forming part thereof.

Figure 1 is a perspective view of a tip for marking implements showing my new design.

Figure 2 is a top plan view of the other end thereof.

Figure 3 is a side elevational view thereof, and Figure 4 is a plan view of the inner end thereof.

I claim:

The ornamental design for a tip for marking implements, as shown.

JOHN P. NISSEN, JR.
